(57) **CLAIM**

The ornamental design for a DIN rail mounting bracket for a controller, as shown and described.

DESCRIPTION

FIG. 1 is a perspective view of a DIN rail mounting bracket for a controller; used for mounting a controller to a DIN rail; FIG. 2 is a front elevation view thereof; FIG. 3 is a top plan view thereof; FIG. 4 is a bottom plan view thereof; FIG. 5 is a left side view thereof; FIG. 6 is a right side view thereof; and, FIG. 7 is a back elevation view thereof the DIN rail mounting bracket of FIG. 1. The broken lines depict portions of the DIN rail mounting bracket for a controller that forms no part of the claim.
